GLUELESS INTERLOCK FOR FOLDING
BOX PANELS

Reginald B. Meller, Oakland, Calif., assignor to
Bemiss-Jason Company, San Francisco, Calif.,
a corporation of California

Application April 17, 1948, Serial No. 21,637

4 Claims. (Cl. 229—35)

1

This invention relates to improvements in cartons, boxes, trays, and other structures made from blanks of cardboard, paperboard, or other suitable foldable sheet material, hereinafter collectively referred to as "boxes" or "folding boxes."

The invention has particular application to folding boxes of the type which are maintained in assembled position by glueless interengagement of the panels or flaps which constitute the box or the box blank.

The invention provides, among other features, an improved interlock for the formation, without the use of adhesives, of a rigid box corner, the box corner being so constructed that it resists, in a heretofore unattained degree, forces which would tend to disengage the interlocking portions of the flaps or panels. More particularly, the invention provides an interlock which is extremely resistant to forces acting at an angle against the walls of the box from the inside of the box and from the outside as well as to forces acting in the planes of the box panels. The result is a gluelessly interlocked box which is extremely resistant to forces exerted on the walls of the box by the box contents, such forces generally acting at right angles with respect to the box walls from the inside, and it is equally resistant to forces acting in the opposite direction, from the outside, the latter type of forces being encountered when the box is tightly overwrapped with a sheet of wrapping material, particularly if the wrapping material has a tendency to shrink.

The invention also provides an improved box corner construction of the aforementioned type permitting insertion of flaps or other portions of a cover or lid between interlocked panels without danger of prying the interlocked panels apart.

While the invention is particularly applicable to the interlocking of panels at a box corner, the invention is not limited to such application but may advantageously be employed wherever it is desired to interlock two panels of a folding box in a rigid manner to form a connection therebetween comparable in strength and rigidity to a glued connection but more convenient, quicker, and less expensive to assemble than a glued box.

The interlock provided by the present invention owes its strength in no small measure to a peculiarity of design which results in the board being subjected to compression rather than tear, compression being the type of force which the board is able to sustain most successfully, whereas tear stress is a far less favorable form of load.

The various objects, features and advantages of the invention will appear more fully from a consideration of the detailed description which

2

follows accompanied by drawings showing, for the purpose of illustration, preferred embodiments and applications of this invention.

The invention also consists in certain new and improved details of construction as hereinafter set forth and claimed.

Although the characteristic features of the invention which are believed to be novel will be particularly pointed out in the claims appended here-to, the invention itself, its objects and advantages, and the manner in which it may be carried out may be better understood by referring to the following description taken in connection with the accompanying drawings forming a part of it in which:

Figure 1 is a plan view of a flat box blank embodying the invention, the inside surface of the blank facing the observer;

Figure 2 is a perspective view of a box set up from the blank shown in Figure 1, certain interlocks being shown in half completed condition;

Figure 3 is a fragmentary plan view of a corner portion of a modified blank, the outside surface of the blank facing the observer; and

Figure 4 is a perspective view of a box made from a blank of the type shown in Figure 3.

In the following description and in the claims, various structural details will be identified by specific names for convenience. The names, however, are intended to be as generic in their application as the art will permit. Corresponding reference characters refer to corresponding parts in the several figures of the drawings.

In the drawings accompanying, and forming part of the specification, certain specific disclosure of the invention is made for the purpose of explanation of broader aspects of the invention but it is understood that the details may be modified in various respects without departure from the principles of the invention and that the invention may be applied to other structures than the ones shown.

The blank A shown in Figure 1 is subdivided by several scored fold lines to provide a bottom or main panel 11 to which side wall panels 12 and 13 are hinged along side fold lines 14 and 15. End wall panels 16 and 17 are hingedly connected to the bottom or main panel 11 along end fold lines 18 and 19, respectively.

Flaps 20 and 21 are hingedly connected to the end panel 16 along fold lines 22 and 23, respectively. The fold lines 22 and 23 are either aligned with, or parallel and slightly offset with respect to, the side fold lines 14 and 15 to compensate for the thickness of the board in the succeeding folding operations, as is customary

in the art. Flaps 24 and 25 are hingedly connected to the end panel 17 along fold lines 26 and 27 in a similar manner as just described.

The flaps 20, 21, 24 and 25 are separated from the side panels 12 and 13 by cuts 28, 29, 30 and 31, respectively, extending to the intersections of the fold lines 14 and 15 with the fold lines 18 and 19. The cuts 28, 29, 30 and 31 include offset portions 32, 33, 34 and 35 which are so shaped as to provide a projecting lock tab 36, 37, 38 and 39 on the side edges of the side panels. The lock tabs 36, 37, 38 and 39 protrude a distance d beyond the side edges of the side panels 12 and 13 formed by the cuts 28, 29, 30 and 31. The length of the lock tabs is preferably of the order of between two to five times the thickness of the board from which the blank is made. The lock tabs form a part of the glueless interlock as will later become apparent.

The interlocks further comprise internal cuts 40, 41, 42 and 43 in the side panels 12 and 13. The internal cuts 40, 41, 42 and 43 separate the panels into portions which may be resiliently flexed with respect to each other for the purpose of opening the cuts and inserting into the opened cuts a portion of the flaps 20, 21, 24 and 25. The internal cuts 40, 41, 42 and 43 are preferably of bent outline to form internal tongues 44, 45, 46 and 47 in the panels 12 and 13. The internal cuts 40, 41, 42 and 43 may extend to the side fold lines 14 and 15, as shown in solid lines, or may be substantially U-shaped as indicated in dotted lines, in which event the portion of the cut shown in solid lines between the broken lines and the side fold lines 14 and 15 would be omitted.

Cut edges 48, 49, 50 and 51 are formed on the flaps 20, 21, 24 and 25 by external cuts 52, 53, 54 and 55 extending into the body of the flaps from outer edges. The orientation and shape of the cuts 52, 53, 54 and 55 is such that portions of the cut edges formed on the flaps 20, 21, 24 and 25 will, upon assembly of the blank into box form, move into substantial coincidence with portions of the internal cuts 40, 41, 42 and 43 so that an edge-to-edge engagement results therebetween as will hereinafter become apparent.

External tongues 56, 57, 58 and 59 are bordered by the external cuts 52, 53, 54 and 55 and an outer edge of the respective flap. These external tongues include tab portions 56', 57', 58' and 59' extending partially beyond the confines of the internal tongues 44, 45, 46 and 47 when the flaps 20, 21, 24 and 25 are folded face-to-face with the side walls 12 and 13 to form box corners. The purpose of the tab portions will become apparent from a consideration of the assembly procedure of the blank which will be described hereinafter.

Internal cuts 60, 61, 62 and 63 preferably of shallow U shape extend near, or substantially in line with, the fold lines 22, 23, 26 and 27, respectively, to provide slits or apertures adapted to receive the lock tabs 36, 37, 38 and 39. In the illustrated embodiment, the cuts 60, 61, 62 and 63 have substantially the form of a flat or shallow U and extend into the body of the adjacent end panels 16 and 17. The cuts form tabs 64, 65, 66 and 67 on the flaps 20, 21, 24 and 25, respectively, which, upon folding of the last named flaps about their fold lines 22, 23, 26 and 27 automatically open apertures into which the lock tabs 36, 37, 38 and 39 fit. The width of these apertures is preferably made equal to one

or two thicknesses of the board so that the respective lock tabs 36, 37, 38 and 39 seat relatively tightly therein without making their insertion difficult in a high speed assembly operation.

The assembly of the blank A into box form may proceed as follows:

The blank A is first folded along the side fold lines 14 and 15 to bring the side panels 12 and 13 into substantially upright position with respect to the bottom panel 11. In this position the stock of the side wall panels 12 and 13 is flexed adjacent the inner cuts 40, 41, 42 and 43 to deflect the internal tongues 44, 45, 46 and 47 outwardly, thereby opening slits in the side wall panels into which the flaps 20, 21, 24 and 25 may thereafter be inserted.

The end panels 16 and 17 are then folded with respect to the bottom panel 11 about the end fold lines 18 and 19, and substantially simultaneously the flaps 20, 21, 24 and 25 are folded with respect to the end panels 16 and 17 about their respective fold lines 22, 23, 26 and 27. This folding operation automatically causes apertures to open at the internal cuts 60, 61, 62 and 63 for insertion of the lock tabs 36, 37, 38 and 39 therein.

The flaps 20, 21, 24 and 25 are brought into parallel position with the upright side wall panels 12 and 13 before the end panels 16 and 17 are fully folded into upright position with respect to the bottom panel, and the erection of the end panels is then continued while simultaneously the portions 56, 57, 58 and 59 of the flaps are guided into the opened slits 40, 41, 42 and 43 in the side panels.

This operation brings the cut edges 48, 49, 50 and 51 into substantial coincidence with portions of the internal cuts 40, 41, 42 and 43 and simultaneously causes the lock tabs 36, 37, 38 and 39 to enter the apertures exposed by the tabs 64, 65, 66 and 67.

The left hand portion of the box illustrated in Figure 2 shows the position which the various portions of the blank assume at the end of the folding operation just described. It will be noted that the assembly of the box corner is complete except for the location of the tab portions 56' and 57' which at this time are on the outside of the side wall panels 12 and 13.

The assembly is completed by pulling the tab portions 56' and 57' to the inside of the box into the position shown by the corresponding tab portions 58' and 59' at the right hand portion of the box as illustrated in Figure 2.

The box corners are now securely interlocked against disengagement. The cut edges 48, 49, 50 and 51 (see Figure 1) engage cut edges formed in the side walls 12 and 13 by the internal cuts 40, 41, 42 and 43 in edge-to-edge relationship. Forces acting against the end panels 16 and 17 from the inside of the box, for example pressure exerted by the box contents, are resisted by the interlock which sustains compressive stress along the interlocked cut edges. Compressive stress is safely sustained by the board since it lies in the plane of the panels in which direction the board offers its greatest resistance to deformation.

Forces acting against the end panels 16 and 17 in the opposite direction are sustained by pressure of the end panels against the side edges 28, 29, 30 and 31 of the side walls 12 and 13.

Pressure exerted against the side walls 12 and 13 from the inside of the box is safely sustained

by the box corners by reason of the reinforcement afforded by the flaps 20, 21, 24 and 25 overlying the side walls.

Forces acting on the side walls 12 and 13 from the outside of the box are resisted by the lock tabs 36, 37, 38 and 39 engaging the apertures in the four box corners. The lock tabs 36, 37, 38 and 39 prevent folding of the side wall panels 12 and 13 towards the inside of the box. Such folding movement, unless prevented by the corner lock tabs 36, 37, 38 and 39, would tend to disengage the cut edges 48, 49, 50 and 51 from the corresponding internal cut edges in the side wall panels 12 and 13.

It is thus seen that the corner tabs 36, 37, 38 and 39 supplement the edge-to-edge interlock formed between the flaps 20, 21, 24 and 25 and the side walls 12 and 13 to prevent disengagement of the edge-to-edge interlock. On the other hand, the edge-to-edge interlock prevents disengagement of the corner tabs 36, 37, 38 and 39 from their respective apertures in the box corner.

In addition, spaces or pockets are formed near the four corners of the box into which portions of a lid or a cover may be frictionally inserted and securely retained without danger of prying the side panels and corner flaps apart. This advantage will become apparent from a consideration of the construction and features of the box shown in Figure 4. The box shown in Figure 4 is made from a blank B of which, for the reason of simplification, only a corner portion is shown which in the finished box forms the box corner B'.

The blank B comprises a bottom panel 68 having a side wall panel 69 connected to it along a side fold line 70. An end panel 71 of equal height as the side panel 69 is hingedly connected to the bottom panel along an end fold line 72. A flap 73 is hingedly connected to the end panel 71 along a fold line 74 which may be aligned with, or be parallel and slightly offset with respect to, the side fold lines 70 to compensate for the thickness of the board as set forth in connection with the previously described blank A.

The flap 73 is separated from the side panel 69 by a cut 75 extending to the intersection of the fold lines 72 and 74. The cut 75 forms a portion of a side edge 76 of the side wall panels 69. The side edge includes a projecting portion or lock tab 77 fitting into an aperture at or near the fold line 74. The apertures may be formed by a slit or a U-shaped cut 78 extending into the body of the end panel 71 and forming a protruding portion 79 on the flap 73 which, upon folding of the flap, automatically opens an aperture adapted to receive the lock tab 77 on the side panel 69.

An internal cut 80 outlines a resiliently deflectable internal tongue 81 in the side wall panel 69 which, upon deflection with respect to the remainder of the side wall panel, permits insertion of a portion of the flap 73 into the resulting slit or aperture.

A cut edge 82 is formed on the flap 73 by an external cut 83 extending into the body of the flap 73. The cut 83 borders an external tongue 84 having a tip portion 85.

The box shown in Figure 4 is assembled by forming and locking the four box corners in the same manner as hereinbefore described in connection with the assembly of the box illustrated in Figure 2. Briefly, the side wall panel 69 is folded into upright position with respect to the bottom panel 68. The end panel 71 and the flap 73

10 15 20 25 30 35 40 45 50 55 60 65 70 75 80 85 90 95 100

73 are then folded about their respective fold lines and the flap 73 is partially inserted into the internal cut 80 after flexing of the internal tongue 81 outwardly with respect to the remainder of the side wall panel 69. The folding operation causes the lock tab 77 to enter the aperture formed by deflection of the tab portion 79. Finally, the tip portion 85 is pulled from the position overlying the side wall panel 69 towards the inside of the box.

The other box corners are assembled in the same manner.

The box comprises a cover 86 hingedly connected to the end wall 87 along a top fold line 88. The cover 86 has depending side flanges of which one is visible at 88. The side flanges are frictionally insertable between the four corner flaps of the box and the respective side panels to maintain the cover in closed position. The cover itself rests on the top edges of the side wall panel, the top edge of the side wall 69 being visible at 89.

The side flanges 88 may be of considerable width and may extend down to the internal cuts 80. The ends of the side flanges are preferably cut away as shown at 90 and 91 in order to clear the lock tabs 77.

A depending front flange 92 may be provided as reinforcement of the front edge of the cover adjacent the end wall 71.

The depending side flanges of the cover 86 frictionally engage the side walls and the four corner flaps. The insertion of cover flanges however, does not interfere with, nor in any way detract from, the strength and reliability of the corner locks since the corner locks are constructed to resist the prying or wedging action of the depending side flanges by the corner lock tabs 77 engaging apertures in the four box corners.

Whereas in the form of box shown in Figure 4 the cover is integral with one end panel of the box, it is evident that the cover may be entirely detached from the box and be provided with depending flanges along all four edges of the cover. This is an obvious modification which, because of its simplicity, requires no further explanation.

The invention thus provides an extremely secure glueless interlock for box panels suitable for assembly on automatic high-speed machinery of relatively simple construction.

As the illustrated forms of boxes show, the invention is equally adaptable to boxes with or without covers. The box shown in Figure 2 is a type of tray which is generally overwrapped with a sheet of transparent wrapping material, such as cellulose acetate. Overwrapped boxes and trays must sustain considerable force from the outside, caused by the tightness of the over-wrap. The present interlock is admirably suited for such boxes or trays since it will withstand considerable forces from the outside. The invention is equally applicable to boxes having either an attached or a separate cover. Four pockets are provided at the four corners of the box into which elements of a cover may be frictionally inserted.

Obviously the present invention is not restricted to the specific embodiments herein shown and described, but may be applied with equal benefit to other forms of boxes. Numerous additions, omissions, substitutions and other changes may be made in adapting the invention to specific needs without departure from the spirit and the essence of the present invention.

What is claimed is:

1. In a box blank of foldable sheet material including, a main panel; a first wall panel hingedly connected to the main panel along a first fold line; a second wall panel hingedly connected to the main panel along a second fold line extending at an angle with respect to the first fold line; and a flap hingedly connected to said first panel along a third fold line extending at an angle with respect to said first fold line, said flap being foldable into face-to-face overlapping position with respect to the second panel, the improvement permitting formation, without the use of adhesives, of said panels and flap into a rigid box corner, the improvement comprising, an internal cut of bent outline in said second panel forming an internal tongue in said second panel adapted to be resiliently flexed with respect to the remainder of said second panel, and an external cut in said flap extending into the body of said flap from an outer edge, said external cut coinciding in interlocking position with a portion of said internal cut in line-to-line, as distinguished from point-to-point coincidence, said external cut forming an external tongue on said flap resiliently deflectable with respect to the remainder of said flap, said external tongue being bordered by said external cut and by at least one outer edge of said flap, the side edge of said second panel lying adjacent and in substantial registry with, said third fold line when said panels are in corner forming position and being shaped to provide a protruding tab on said second panel, said third fold line including a U-shaped cut extending into the body of said first panel and forming a tab on said flap, the U-shaped cut producing a self-opening aperture along said third fold line when said flap is folded with respect to said first panel, said aperture being adapted to receive the tab on said second panel, said flap being partially insertable through said internal cut and under said internal tongue, said internal and external cuts being so located with respect to each other and with respect to said tab and aperture that portions of the two cuts are in substantial coincidence, permitting an edge portion formed by one cut to engage a coinciding edge portion formed by the other cut in edge-to-edge, as distinguished from point-to-point, position when said tab extends into said aperture, said engaged edge portions locking said flap and second panel against parallel shifting with respect to each other, said tab and aperture preventing separation of said flap and second panel from their face-to-face position which would tend to disturb the edge-to-edge engagement, whereby the corner is securely locked to resist forces acting both in the planes of, and at an angle to, said flap and panels both from the inside and from the outside of the corner.

2. In a box blank of foldable sheet material including, a main panel; a first wall panel hingedly connected to the main panel along a first fold line; a second wall panel hingedly connected to the main panel along a second fold line extending at an angle with respect to the first fold line; and a flap hingedly connected to said first panel along a third fold line extending at an angle with respect to said first fold line, said flap being foldable into face-to-face overlapping position with respect to the second panel, the improvement permitting formation, without the use of adhesives, of said panels and flap into a rigid box corner, the improvement comprising, an internal cut of bent outline in said second panel forming an internal tongue in said second panel adapted to be resiliently flexed with respect to the remainder of said second panel and an external cut in said flap extending into the body of said flap from an outer edge, said external cut coinciding

in interlocking position with a portion of said internal cut in line-to-line, as distinguished from point-to-point coincidence, said external cut forming an external tongue on said flap resiliently deflectable with respect to the remainder of said flap, said external tongue being bordered by said external cut and by at least one outer edge of said flap, the side edge of said second panel lying adjacent and in substantial registry with, said third fold line when said panels are in corner forming position and being shaped to provide a protruding tab on said second panel, said third fold line including a U-shaped cut extending into the body of said first panel and forming a tab on said flap, the U-shaped cut producing a self-opening aperture along said third fold line when said flap is folded with respect to said first panel, said aperture being adapted to receive the tab on said second panel, said flap being partially insertable through said internal cut and under said internal tongue, said internal and external cuts being so located with respect to each other and with respect to said tab and aperture that portions of the two cuts are in substantial coincidence, permitting an edge portion formed by one cut to engage a coinciding edge portion formed by the other cut in edge-to-edge, as distinguished from point-to-point, position when said tab extends into said aperture, said engaged edge portions locking said flap and second panel against parallel shifting with respect to each other, said tab and aperture preventing separation of said flap and second panel from their face-to-face position which would tend to disturb the edge-to-edge engagement, whereby the corner is securely locked to resist forces acting both in the planes of, and at an angle to, said flap and panels both from the inside and from the outside of the corner.

3. In a box blank of foldable sheet material including a main panel; a first wall panel hingedly connected to the main panel along a first fold line; a second wall panel hingedly connected to the main panel along a second fold line extending at an angle with respect to the first fold line; and a flap hingedly connected to said first panel along a third fold line extending at an angle with respect to said first fold line, said flap being foldable into face-to-face overlapping position with respect to the second panel, the improvement permitting formation, without the use of adhesives, of said panels and flap into a rigid box corner, the improvement comprising, an internal cut of bent outline in said second panel forming an internal tongue in said second panel adapted to be resiliently flexed with respect to the remainder of said second panel and an external cut in said flap extending into the body of said flap from an outer edge, said external cut coinciding in interlocking position with a portion of said internal cut in line-to-line, as distinguished from point-to-point coincidence, said external cut forming an external tongue on said flap resiliently deflectable with respect to the remainder of said flap, said external tongue being bordered by said external cut and by at least one outer edge of said flap, the external tongue being of such outline relatively to the outline of said internal cut that a tab portion of said external tongue extends beyond the confines of said internal tongue of the flap and the second panel are placed face-to-face in the position in which they are to be interlocked, the side edge of said second panel lying adjacent, and in substantial registry with, said third fold line when said panels

are in corner forming position and being shaped to provide a protruding tab on said second panel, said third fold line including a U-shaped cut extending into the body of said first panel and forming a tab on said flap, the U-shaped cut producing a self-opening aperture along said third fold line when said flap is folded with respect to said first panel, said aperture being adapted to receive the tab on said second panel, said flap being partially insertable through said internal cut and under said internal tongue, said internal and external cuts being so located with respect to each other and with respect to said tab and aperture that portions of the two cuts are in substantial coincidence, permitting an edge portion formed by one cut to engage an edge portion formed by the other cut in edge-to-edge, as distinguished from point-to-point, position when said tab extends into said aperture and said tab portion is forced through said internal cut from a position overlying said second side panel into a position underlying said second side panel, said engaged edge portions locking said flap and second panel against parallel shifting with respect to each other, said tab and aperture preventing separation of said flap and second panel from their face-to-face position which would tend to disturb the edge-to-edge engagement, whereby the corner is securely locked to resist forces acting both in the planes of, and at an angle to, said flap and panels both from the inside and from the outside of the corner.

4. In a box blank of foldable sheet material including a main panel; a first wall panel hinged-ly connected to the main panel along a first fold line; a second wall panel hingedly connected to the main panel along a second fold line extending at an angle with respect to the first fold line; and a flap hingedly connected to said first panel along a third fold line extending at an angle with respect to said first fold line, said flap being foldable into face-to-face overlapping position with respect to the second panel, the improvement permitting formation, without the use of adhesives, of said panels and flap into a rigid box corner, the improvement comprising, an internal cut in said second panel, and an external cut in said flap extending into the body of said flap from an outer edge, said external cut coinciding in interlocking position with a portion of said internal cut in line-to-line, as distinguished from point-

to-point coincidence, said external cut forming an external tongue on said flap resiliently deflectable with respect to the remainder of said flap, said external tongue being bordered by said external cut and by at least one outer edge of said flap, a tab projecting from a side edge of said second panel towards said first panel when the panels are in corner forming position, said side edge being in substantial registry with said third fold line in corner forming position, and an aperture in said first panel along said third fold line adapted to receive said tab, said flap being partially insertable through said internal cut, said internal and external cuts being so located with respect to each other and with respect to said tab and aperture that portions of the two cuts are in substantial coincidence, permitting an edge portion formed by one cut to engage an edge portion formed by the other cut in edge-to-edge, as distinguished from point-to-point position when said tab extends into said aperture and when the side edge of said second panel abuts the surface of said first panel in edge-to-surface position, said engaged edge portions locking said flap and second panel against parallel shifting with respect to each other, said tab and aperture preventing separation of said flap and second panel from their face-to-face position which would tend to disturb the edge-to-edge engagement, whereby the corner is securely locked to resist forces acting both in the planes of, and at an angle to, said flap and panels both from the inside and from the outside of the corner.

REGINALD B. MELLER.
